SURFBOARD

Richard G. Kirchner, San Diego, Calif.

Application November 18, 1940, Serial No. 366,052

5 Claims. (Cl. 9—11)

This invention relates to aquatic amusement devices and in particular to surf boards.

One object of this invention is to provide a surf board having means associated therewith for increasing the driving effect of the wave upon the surf board.

Another object is to provide a surf board having a step on the bottom which catches the swirl of the crest of a wave and increases the propulsive effect thereof.

Another object is to provide a surf board as set forth in the preceding object wherein the step is V-shaped, so that a tendency of the board to yaw or turn is counteracted by the pressure being increased on one side of the V step and lessened on the other side.

Another object is to provide a surf board having a plurality of steps on the bottom, these steps providing portions for the whirling crest of the wave to grip, thereby increasing the efficiency of the surf board by enhancing the propelling force thereon.

In the drawing:

Figure 1 is a top plan view of a surf board with a V-shaped step, according to one embodiment of the invention.

Figure 2 is a side elevation of the surf board shown in Figure 1.

Figure 3 is a top plan view of a modified form of surf board having a straight step.

Figure 4 is a top plan view of a modified form of surf board having a plurality of V-shaped steps.

Figure 5 is a side elevation of the surf board shown in Figure 4.

Figure 6 is a diagrammatic side elevation of the surf board of Figures 1 and 2 in use.

In general, the surf board of this invention consists of an elongated floating member, such as a wooden plank, having a step on the bottom thereof. The step is either V-shaped or extends straight across the surf board. A further modification contemplates the use of a plurality of steps on the bottom of the surf board. The step on the bottom of the surf board increases the propelling effect by giving an abutment which the whirling crest of the wave can grip. The V-shaped step makes the surf board partially self-steering since any tendency of the board to yaw or turn is counteracted by the pressure being increased on one side of the V and decreased on the other side.

Referring to the drawing in detail, Figure 1 shows a surf board 10 having a pointed bow 11, curved stern 12, and longitudinal sides 13. The surf board 10 is provided with an upper surface 14

and lower surfaces 15 and 16 on different levels and separated by a V-shaped step 17 having relatively angled portions 18 and 19. As shown in Figure 2, the lower surfaces 15 and 16 are sloped relatively to one another so that the surf board is thicker at the step 17 than it is at the bow 11 or stern 12.

The modified form of surf board 20 shown in Figure 3 is generally similar to that shown in Figure 1 as far as its general outline is concerned. The surf board 20, however, is provided with a straight step 21 which extends across the bottom of the surf board at right angles to the sides 13 thereof, instead of the V-shaped step 17 of Figure 1.

The modified form of surf board 30 shown in Figures 4 and 5 is generally similar to that shown in Figure 1 except that the bottom surfaces 15 and 16 are separated by multiple V-shaped steps 31 and 32 having relatively angled walls 33, 34, 35 and 36 respectively. This surf board is thus similar to that of Figure 1, but with an additional step provided.

In the operation of the surf board, the user swims out with the board or is towed out by boat to a point where large waves begin to roll in toward the shore. The swimmer then turns the surf board toward the shore, such as by paddling it around with his hands.

When the crest of a large wave comes beneath the surf board, this crest grips the step on the surf board as it whirs onward, propelling the surf board rapidly toward the shore. Thus the step catches the swirl at the top of a wave and enhances the driving power of the wave upon the surf board.

The V-shaped step of Figures 1, 2, 4 and 5 makes the surf board at least partially self-steering, as compared with the surf board of Figure 3 with its straight step. The multiple or plural steps of the surf board of Figures 4 and 5 distribute the thrusting effect of the wave between the two sets of shoulders provided by the two steps.

The sport of surf riding cannot be practised at every beach but is confined to beaches where the water is sufficiently shallow and the approach sufficiently gradual so that large waves will be created and will roll rapidly toward the shore. The ordinary surf board with its comparatively smooth bottom is therefore capable of use only in a few limited locations. The surf board of the present invention, however, can be used at many beaches where the ordinary surf board would be comparatively useless since the step

on the bottom of the present surf board is gripped by the whirling crest of the wave and thus the bottom is propelled rapidly, where without this step it would be propelled too slowly or not at all.

While a specific embodiment of the invention has been described and illustrated, it will be understood that various modifications may be made within the scope of the appended claims without departing from the spirit of the invention.

What I claim is:

1. A wave propelled surf board comprising an elongated plank member relatively thin in proportion to its length and width and having inclined bottom walls converging from the front and rear of said board to the intermediate portion thereof and terminating at their inner ends on different levels, obliquely-disposed vertical walls connecting said inclined bottom walls at their point of termination to provide an intermediate V-shaped stepped shoulder portion adapted to be engaged by the crest of a wave.

2. A wave propelled surf board comprising an elongated plank member relatively thin in proportion to its length and width and having a flat plane upper surface and a plurality of inclined bottom surfaces sloping relatively to one another toward the middle from relatively thin ends and terminating on different levels, said inclined bottom surfaces being connected by a vertical wall at their point of termination to provide a shoulder therebetween, and said shoulder being formed at a location to be engaged by the crest of a wave.

3. A wave propelled surf board comprising a

relatively long and narrow plank member relatively thin in proportion to its length and width and having inclined bottom walls sloping from the ends to the intermediate portion of said board and terminating on different levels, a vertical wall extending between the terminating points of said inclined bottom walls, said walls providing a transversely disposed step on the underside thereof, said step being horizontally V-

5 shaped and located centrally on the underside of the surf board to be engaged by the crest of a wave.

4. A wave propelled surf board comprising an elongated plank member relatively thin in proportion to its length and width and having a plurality of similarly arranged horizontally V-shaped steps on the underside thereof, said V-shaped steps being adjacent one another and being approximately centrally positioned so as

20 to be engaged by the crest of a wave.

5. A wave propelled surf board comprising an elongated plank member relatively thin in proportion to its length and width and having a plurality of bottom surfaces in different planes

25 separated from one another by a step, said step having vertical walls extending obliquely from the edges of the board in a horizontally V-shaped path with the arms of the V converging toward a junction at the center thereof, said vertical walls being positioned intermediate the ends of the board in a location to be engaged by the crest of a wave.

RICHARD G. KIRCHNER.
